(57) **CLAIM**

The ornamental design for a bottle, as shown and described.

DESCRIPTION

FIG. 1 is a bottom, front, and left side perspective view of a
first embodiment of the invention;

FIG. 2 is a left side elevational view thereof, the right side
elevational view being identical;

FIG. 3 is a front elevational view thereof, the back elevational
view being identical;

FIG. 4 is a top plan view thereof;

FIG. 5 is a bottom plan view thereof;

FIG. 6 is a bottom, front, and left side perspective view of the
bottle of FIG. 1 shown with a cap thereon, the front, left side,
right side, and back elevational views of the cap being identical;

FIG. 7 is a top plan view of the bottle shown in FIG. 6;

FIG. 8 is a top, front, and right side perspective view of a
second embodiment of the invention;

FIG. 9 is a right side elevational view thereof, the left side
elevational view being identical;

FIG. 10 is a front elevational view thereof, the back eleva-
tional view being identical;

FIG. 11 is a top plan view thereof;

FIG. 12 is a bottom plan view of the bottle shown in FIG. 8
and a bottom plan view of the bottle shown in FIG. 15;

FIG. 13 is a left side elevational view of the bottle of FIG. 8
shown with a cap, thereon, the front, left side, right side, and
back elevational views of the cap being identical;

FIG. 14 is a top plan view of the bottle shown in FIG. 13;

FIG. 15 is a top, front, and right side perspective view of a
third embodiment of the invention;

FIG. 16 is a left side elevational view thereof, the right side
elevational view being identical;

FIG. 17 is a front elevational view thereof, the back eleva-
tional view being identical;

FIG. 18 is a top plan view thereof;

FIG. 19 is a left side elevational view of the bottle of FIG. 15
shown with a cap, thereon, the front, left side, right side, and
back elevational views of the cap being identical; and,

FIG. 20 is a top plan view of the bottle shown in FIG. 19.

The broken lines shown in the drawings are for environmental
purposes only and form no part of the claimed design.
